UNITED STATES PATENT OFFICE.

CHARLES LOCKHART AND JOHN GRACIE, OF PITTSBURG, PENNSYLVANIA.

IMPROVEMENT IN STILLS FOR PETROLEUM, &c.

Specification forming part of Letters Patent No. 40,632, dated November 17, 1863.

To all whom it may concern:

Be it known that we, CHARLES LOCKHART and JOHN GRACIE, of Pittsburgh, in the county of Allegheny and State of Pennsylvania, have invented certain new and useful Improvements in Stills for Distilling Petroleum or Coal Oil; and we do hereby declare that the following is a full, clear, and exact description of the same, reference being had to the accompanying drawings, making a part of this specification, in which—

Figure 1 is a side sectional view of a still constructed according to our invention; Fig. 2, a plan or top view of the same, the stuffing-box being bisected horizontally, as indicated by the line *y y*, Fig. 1; Fig. 3, a detached inverted plan of scrapers pertaining to the same.

Similar letters of reference indicate corresponding parts in the several figures.

This invention relates, first, to a means for taking off vapor from the still at the same height from the surface of the oil and at different heights during the process of distillation; second, to a means for keeping the bottom of the still clean or free from incrustation.

A represents the still, and B the top thereof, in which a pipe, C, of curved or goose-neck form, is fitted and permanently secured; and D is a straight horizontal pipe, the inner end of which communicates with C near its lower end, and the outer end of C communicating with D near its center, the two pipes having a common outlet. Each pipe, near the inner junction of the two, is provided with a valve, E, by which either pipe may be closed and the vapor allowed to escape to the condenser through either of them, as may be desired. This will be fully understood by referring to Fig. 1. The advantage of this arrangement is as follows: The pipe C is used at the commencement of the "run" or distilling process, as the still can be run fast without any of the fluid passing over mechanically, as all unvaporized oil will fall back into the still, while the dry vapor will pass through C into the condensers, making white oil. When, however, the oil gets low in the still, the vapor of course must ascend higher, the height increasing in proportion to the gradual descent of the oil in the still, which oil and vapor gradually increases in density as the distilling process progresses, and a large portion of this heavy vapor, if the pipe C is used, would con-

dense within it, and there would be a continual falling back of oil, owing to repeated condensation and redistillation and a great loss of permanent gas. The correct principle, therefore, is to bring the discharge or vapor-conducting pipe nearer the surface of the oil as the latter gets heavy or increases in density, and this we effect by using the pipe D and closing C, so that there will at all times be a free passage for the vapor.

The bottom *a* of the still is of cast-iron, in one piece. The other portion, *b*, (the siding,) is of wrought-iron, as that is not exposed to a great degree of heat. The advantage of this construction is as follows: The ordinary stills are made with sheet-iron bottoms, a number of sheets being riveted together, and these bottoms, when coated with residuum, are necessarily subjected to a very great heat, and the sheets warp, the seams open, and leakage ensues. This difficulty is fully obviated by our improvement, which possesses the advantage of admitting of the bottom being of any form desired, it being as easy to cast it of one form as another, and in one piece, without any seams or joints, whereas the ordinary sheet-metal bottoms cannot be constructed of sheet or wrought metal without seams or joints.

F represents a shaft which is placed vertically in the still and passes up through a stuffing-box, G, at the center of the top B thereof. On the lower end of this shaft F there is fitted a plate, H, to two opposite edges of which plates I are attached by hinges or joints *c c*. These plates I are curved to correspond to the curvature of the bottom *a* of the still, and said plates have scrapers *d* attached to their under surface, which rest on the bottom *a*, as shown in Fig. 1. The lower end of the shaft F is fitted in a step, *e*, at the center of the bottom *a* of the still, and the upper end of said shaft above the top B of the still has a pulley, *f*, or a gear-wheel upon it, by which the shaft is rotated. By rotating this shaft the scrapers *d* are made to work over the bottom *a* of the still, and all sediment will be scraped therefrom.

The sediment or residuum in petroleum-stills is principally earthy matter and a carbonaceous matter resembling the carbon that accumulates in gas-retorts during the process of distillation. This settles to the bottom, burning to a hard crust of from one to six inches in thickness, and if a strong heat is kept up

for a short time the crust becomes as hard as the iron itself, and it is then impossible to get heat enough to penetrate through this mass of incrustation without burning the still-bottom. Our invention fully obviates this difficulty. The stuffing-box *G*, if of the ordinary kind, would not answer, owing to the great heat to which it would be subjected on the still. To obviate this difficulty we cast the box with an annular space, *g*, all around it, and have a stream of water passing around it, the water passing into sail space through a pipe, *h*, and discharged from it through a pipe, *i*, as shown in Fig. 2. By this means the stuffing-box will be protected from the great heat of the still.

To the center of the bottom *a* of the still there is attached a receiver, *H'*, into which the sediment falls as it is scraped from the bottom *a* of the still. As the sediment or heavy mat-

ter falls into the receiver it of course displaces the oil therein, the receiver being filled with oil when the still is filled, as there is no cut-off between them.

Having thus described our invention, what we claim as new, and desire to secure by Letters Patent, is—

1. The combination, with the goose-neck *C*, of the horizontal or lower pipe, *D*, and valves *E* *E*, in the manner herein shown and described.
2. The combination of the curved hinged plates *I* and attached scrapers *d* with the shaft *F* and bottom *a*, in the manner herein shown and described.

CHARLES LOCKHART.
JOHN GRACIE.
